UNITED STATES PATENT OFFICE.

WILLIAM COBURN AND CHARLES W. DAVIS, OF SEATTLE, WASHINGTON, ASSIGNEES
TO UNIVERSAL STERILIZING COMPANY, OF SEATTLE, WASHINGTON, A CORPORATION
OF WASHINGTON.

WATER-DISTRIBUTUTING MECHANISM.

1,139,848.

Specification of Letters Patent.

Patented May 18, 1915.

Original application filed January 26, 1914, Serial No. 814,502. Divided and this application filed April 15, 1914. Serial No. 831,992.

To all whom it may concern:

Be it known that we, WILLIAM COBURN and CHARLES W. DAVIS, citizens of the United States of America, residing at 5 Seattle, in the county of King and State of Washington, have invented certain new and useful Improvements in Water-Distributing Mechanisms, of which the following is a specification, the same being a division 10 of our application for patent for washing-machines, filed January 26, 1914, Serial No. 814,502.

This invention relates to mechanisms of the above character especially adapted for 15 machines for washing tumblers, glasses and other ware, and it has for its primary object to provide a device or mechanism to efficiently operate and be easily controllable.

A further aim of the invention resides in 20 the novel mechanisms by which fluids of differing qualities may be successively ejected into the chamber containing the glasses or other articles.

Other important objects will be set forth 25 as the description progresses, and the salient features of construction, arrangements and combinations of parts on which we desire protection will be succinctly brought out in the annexed claims.

For a full understanding of the invention 30 reference is had to the following specification and the accompanying drawings wherein like characters of reference designate similar parts throughout.

In the drawings Figure 1 is a side elevation 35 of the washing machine with the carriage removed from the washing chamber and illustrating in dotted lines the hood closed and the operating lever partially depressed for opening the hot water pipe.

Fig. 2 is a front view of the machine shown 40 partly in elevation and partly in section. Fig. 3 is an elevation similar to Fig. 1 with portions broken away for the sake of clear-

ness and the operating lever fully depressed 45 to shut off the hot water and open the cold water pipe. Fig. 4 is a longitudinal vertical section of the construction. Fig. 5 is a top plan thereof. Figs. 6 and 7 are sectional

50 views of fragmentary portions of the invention taken respectively along lines 6—6 and

7—7 of Fig. 5, and Fig. 8 is a view in elevation of the hood opening mechanism and the trip arm for releasing the carriage.

It may be preliminarily mentioned that in 55 the preferred embodiment of the invention, illustrated in the accompanying drawings, there are employed a chamber, a nozzle in the chamber and connected to a plurality of fluid conducting pipes in which are arranged valves, and an actuator for controlling the valves for successively opening and closing the same, said actuator including, broadly, a plurality of mechanisms certain of which control the fluid supply to the 60 nozzle.

Referring more in particular to the drawings, the main frame 1 supports a washing chamber 2 which is provided with a sloping bottom 3 to facilitate the draining of the 70 liquid therefrom through drain pipe 4. A partition wall 5 extends downwardly within the chamber from the top to divide the same into forward and rear compartments 6, 7. A foraminous shelf or table 8 caps the forward compartment to serve as a drain support while the rear compartment is superimposed by a hood 9 hinged to the frame 1 and forming a closure for the compartment. A ledge 10 extends upwardly from the rear 80 edge of shelf 8 to form a seat for the forward edge of hood 9.

Spaced track elements 11, suspended at a plane above the table, provide means over which the carriage 12 may traverse. Trac- 85 tion wheels 13 support the carriage on the track while guards or hook shaped members 14 depend therefrom and terminate beneath the track to be adaptable for engagement with the latter on movement tending 90 to dislodge the carriage.

The carriage is provided with a basket 15, preferably removable, for carrying the tumblers or glasses to be washed and has a depending lug 16 which, when the carriage 95 is in compartment 7, engages a spring actuated catch 17 which is vertically retracted by its trip arm 18 being engaged by dog 19 pivoted to a downwardly extending arm 20 fixed on an end wall of the hood. The dog 100 is pivoted to afford a yielding action on closing the hood whereby the trip arm will

remain undisturbed. A weight 21, suitably guided on partition wall 5, is connected to the rear of the carriage by a flexible member 22, after taking over guide 23, whereby, on the catch or lock 17 releasing the carriage, the latter is automatically moved along the track from the compartment 7 to the table 8. A hasp or apertured tongue 24 of the hood passes through an opening in the table, on closing the hood, and is engaged by a latch 25 which is connected to a trip bell-crank lever 26 mounted exteriorly of the main frame whereby on tripping it the hood may be automatically opened through a system of spring actuated links 27 connected to fixed arm 20. An upwardly facing spray nozzle 28 is disposed in compartment 7 above the lower edge of wall 5 for directing the washing fluid upwardly against the tumblers, said nozzle being connected by pipe or conduit 29 to the hot and cold water pipes 30 and 31, respectively, which are each provided with a valve or cock 32, 33.

25 Mounted in guides 34 of the main frame for vertical sliding, is an actuator 35 normally held in its uppermost position by spring 36 seating on the lower guide 34 and operable against the tendency of the spring 30 by a lever 37, preferably of the foot type, pivotally supported on the frame by link 38 and projecting forwardly in front of the machine. The forward end of the lever terminates in a pedal 39 and is guided by a strap 40 of the main frame, said strap being provided with a stop 41 for engaging the lever during depression of the latter, as shown in dotted lines in Fig. 1. Lateral movement of the lever will free it of the 40 stop for further depression.

The valves or cut-offs are provided with bell-crank operators 42, 43 pivoted for opening the valves against the action of the valve springs and having the longer arms projecting in proximity to the actuator slide. The longer arm of bell-crank 43 operates through slot 2' of the chamber and is engaged by lug 44 of actuator 35 subsequent to the lever 37 passing the stop 41, on further depression thereof. Prior to the lever engaging the stop 41 the longer arm of crank 42 is engaged by a pawl 45, carried on the actuator slide, to open the hot water valve. A spring actuated, pivoted catch 46, on the main frame engages over the longer arm of bell-crank 42, when depressed to open the valve, to maintain the latter open independently of the pawl 45, thereby permitting of the slide returning to normal position. Should it be desired to close the valve without manipulating the slide, which latter operation necessitates the opening of the cold water pipe in priority, the catch 46 may be moved to release the bell-crank by a handle extension 46'.

Subsequent to the catch or lock engaging the bell-crank 42, the pawl 45 is freed from the latter, to permit of the actuator 35 being operated to perform its further functions, by a rearward extension 45' riding on the upper face 47' of a double cam 47 fixed on the main frame. On upward movement, the pawl is set for the succeeding operation by the rear face thereof engaging the lower face 47'' of the fixed cam. A dog 48 fixed on the upper end portion of the actuator rides the cam 49 of the catch 46 for releasing the bell-crank to effect a closing of the hot water conduit prior to opening the cold water pipe by dog 44. Dog 48 serves as a support for a pivoted dog 50 adapted to yield in passing downwardly by trip 26 and formed with a lug 50' to engage the actuator slide for maintaining the dog rigid on upward movement of the slide to effect a rocking of said trip to release the hood.

The operation, although obvious from the foregoing, will be briefly set forth. The glasses or tumblers being positioned in the basket on the carriage, the latter is moved from table 8 to the compartment 7 of the washing chamber where the latch 17 locks it from movement by the advancing means 21. The hood is then closed and the lever 37 depressed until limited by stop 41. The lever thus far has opened the hot water which washes and sterilizes the glasses. For obvious reasons this spray may be maintained by lock 46, which has engaged over the bell crank 42 on the latter having been moved by the pawl 45, until released either manually or by the actuator. The operating or controlling lever is further depressed to successively bring the dogs 48 and 44 to a position to perform their designated functions namely, closing valve 32 and opening valve 33. The cold water spray rinses and cools the glasses for immediate use. The lever is then released and the actuator, aided by spring 36, returns to its normal position which in so doing, permits valve 33 to close and through dog 50 releases the hood for opening by the spring actuated connection 27. When the hood is practically opened, dog 19 trips arm 18 to release the carriage which is then advanced over table 8 by the weight 21. It will be noted that the remaining hot water in the pipe 29, after closing valve 32, gradually tempebrates the spray against the glasses on opening valve 33 and vice versa. It is, of course, obvious that other washing fluids may be utilized.

The foregoing detailed description has been given for clearness of understanding only, and no undue limitation should be understood therefrom. Hence, the appended claims should be construed as broadly as permissible in view of the prior art.

Having thus described our invention, what

we claim as new, and desire to secure by Letters Patent of the United States of America, is:—

1. In a machine of the character described, liquid directing means, a conduit connected thereto, valve means in the conduit, an actuator, means on the actuator for opening the valve means, means for releasing the valve means from the actuator means, means for maintaining the valve means opened subsequent to releasing of the same by the actuator means, and means operable by the actuator for positively releasing the valve means from said means maintaining the latter opened.

2. In a machine of the character described, liquid directing means, a conduit connected thereto, valve means in the conduit, an actuator, means on the actuator for opening the valve means, means for releasing the valve means from the actuator means, means for positively maintaining the valve means opened subsequent to releasing of the same by the actuator means, and means operable by the actuator for positively releasing the valve means from said means maintaining the latter opened.

3. In a machine of the character described, liquid directing means, a conduit connected thereto, valve means for controlling the flow of liquid, an actuator for opening the valve

means, means for locking the valve means opened, and cam means operable by the actuator to release the valve means from the lock means.

4. In a machine of the character described, liquid directing means, conduits connected therewith, valve means for the conduits, an actuator for opening the valve means of each conduit in succession, means independent of the actuator for locking one valve means opened, and means operable by the actuator for releasing the valve means from the lock means.

5. In a machine of the character described, liquid directing means, conduits connected therewith, valve means for the conduits, an actuator for opening the valve means of each conduit in succession, means for closing one valve means prior to the opening of the succeeding valve means, and stop means adapted to stop the actuator intermediate the opening of the first valve means and the succeeding valve means.

In testimony whereof we affix our signatures in presence of two witnesses.

WILLIAM COBURN.
CHARLES W. DAVIS.
